CURTAIN ROD

Joseph V. Graber and Ferdinand F. Salzmann, Madison, Wis., assignors to Graber Manufacturing Company, Inc., Middleton, Wis., a corporation of Wisconsin

Filed Apr. 14, 1965, Ser. No. 84,773

Term of patent 14 years

(Cl. D21—1)

FIGURE 1 is a front perspective view of a curtain rod showing our new design;

FIG. 2 is a top plan view thereof;

FIG. 3 is a front elevational view thereof; and

FIG. 4 is a cross-sectional view through the rod on a larger scale.

The break in the center of the rod and the dotted lines spanning the break are intended to indicate indeterminate or indefinite length.

The essential features of the design reside in the portions shown in solid lines on the drawing.

The broken line showings of the brackets in FIGS. 1-3 are for illustrative purposes only.

We claim:

The ornamental design for a curtain rod, substantially as shown and described.
